UNITED STATES PATENT OFFICE.

JOHN SCHIMMELPFENNIG, OF CEDAR RAPIDS, IOWA.

COMBINATION WOODWORKING MACHINE.

Application filed January 24, 1925. Serial No. 4,579.

This invention relates to machines used chiefly for finishing hard-wood floors by sandpapering, and the object of the invention is to produce a machine capable of performing this operation in a simple and satisfactory manner, and is also adaptable for sanding door and window trim, and for sawing, boring, and the like operations in the finishing of house interiors.

The machine has been designed to remove the most common drawbacks to the use of the floor-sander in general use. This is commonly a heavy machine, requiring the efforts of two or more men to move it from one floor to another, and using an electric motor too large to be operated by the ordinary lighting current. It can thus be used but rarely in new houses of moderate size and cost, because of the expense and trouble of installing special wiring, and all the other incidentals. The machine about to be described, however, is operable from the regular lighting system, and can be plugged in wherever a light socket is available. It is also portable by one man, by removing the motor, and carrying the machine as two separate loads.

The invention is fully disclosed in the description and claim following, reference being had to the accompanying drawings, in which:—

Fig. 1 is a view in perspective of the right side of the machine used as a floor-sander. Fig. 2 is a similar view of the opposite side of the operative parts of the machine. Fig. 3 is an elevation showing the right side with one of the carrying wheels removed. Fig. 4 is a similar elevation, the housing being in central, longitudinal section. Fig. 5 is a front view in perspective, showing the application of the machine to sawing, boring, and the sanding of strip lumber. Fig. 6 shows a part of the framework of Fig. 5, and illustrates the mounting of the sanding machine thereon.

The main body of the machine, 5, is a practically rectangular box or case, hereafter designated as the housing. It is open at the front end to give access to the sanding roller 6, the opening being closed during the operation of the machine by a hood or flap 7 hinged at 8. The roller is of a familiar type, with a groove at 9 to receive a key or wedge 10 by means of which the sandpaper sheet 11 is held in place. Its extended journals 12 run in bearings 13. One journal car-

ries a pulley 14, by which the roller is driven, as will be explained presently. Outside of the pulley the shaft is extended, as shown in Fig. 2, and preferably provided with a pin-hole 15, whereby it may be readily supplied with another pulley, or quickly connected with a saw-arbor, as will be set forth more fully hereafter. The other end is also extended, so as to carry an auxiliary sanding roller 16, as shown in Fig. 5, whereby the sanding of a floor may be carried close to the base-board. This roller may be applied to the other end of the shaft if desired.

The housing is closed at the top by a cover 17, and on this is mounted an electric motor 18, which is supposed to connect for operation with any lamp-socket by a suitable drop-cord 19. Its pulley 20 connects by a belt 21 with the pulley 14. The proper tension is applied to this belt by an idler 22 carried by a cranked rock-shaft 23 mounted in bearings 24. A spring 25 connects with the crank at 26, and is drawn or relaxed by a notched plate 27 engaging a stud or screw 28.

At each side of the main housing is pivoted a wheel-bearing plate 29 provided with a hollow gudgeon 30, on which revolves a carrying wheel 31, held in place by a cap-ring 32. Each of these wheels is of practically the same diameter as the sanding roller. Each projecting side of the cover is provided with an adjusting screw 33 abutting on the bearing-plate as shown in Fig. 3. It is evident that the screwing of these screws downwardly will tend to lift the front end of the housing and the roller from the floor, the weight of the parts, and the superimposed motor operating in the opposite direction. By this means it is possible to adjust the roller with all the desired accuracy to the surface to be sanded, and the operator has then only to run the machine over the surface, and depend entirely on the machine so adjusted to produce a smooth and level surface.

At the rear, the housing is carried by a castor-wheel 34 detachably swiveled in a bearing 35. As the carrier-wheels are mounted concentric to the sanding roller, it is evident that the adjustment of the abrasive to the floor surface is not affected by the lift or depression of the castor, and whether it be running over a rise, or a hollow, the sanding contact remains unchanged.

Provision is made for quickly lifting or depressing the sanding-roll without chang-

ing the adjustment. At each side of the housing is pivoted a bell-crank lever 36, one arm of which engages the wheel-bearing plate, and the other is linked by a connecting-rod 37 with a bail lever 38, pivoted to the housing at 39. A stop-stud 40 limits the downward movement of this lever. Depressing this lever by the toe lifts the sanding-roll off the floor, and a lift of the lever by the toe restores it to its former position.

The machine is propelled by a handle 41 attached to a bracket 42. The handle serves as a support for a dust-bag 43 slung under the handle, its lower, open end secured to an outlet 44 at the rear of the housing. This outlet communicates with a fan-case 45 inside the housing, and in this is a small fan 46 adapted to receive the dust of the sanding operation and throw it into the dust-bag. The fan is driven by a belt 47 running on pulleys 48 and 49. An opening in one side of the housing, closed normally by a plate 50, gives access to the interior, to clear the fan of any obstruction.

In Figs. 5 and 6, the machine is shown as adapted for other operations. A frame serves as a support for the machine, and comprises sills 51 and a series of cross-beams. Two of these, 52, are provided at the rear with a bridge 53 carrying a central stud 54 to enter the socket at the rear of the housing when the castor is removed. On one of the cross-beams is a hollowed plate 55 to receive the tread of one of the carrying wheels, a flat plate 56 serving for the other. This holds the machine securely in a fixed and definite position. Between the beams 52 is mounted a bottom-board 57, provided with lateral brackets 58 and adjusting screws 59, whereby the front end of the board may be raised or depressed. Adjusted to the proper thickness of casing material, the board serves as an accurate guide for such material, which is run through under the sanding-roll and given a smooth finish.

On a cross-beam 60 is mounted a pair of sockets 61 to receive the stems of an angled guide-plate 61^a set over the auxiliary sanding-roll, and adjustable by means of hand-screws 62. This serves as a guide by means of which the edges of material may be smoothly and accurately finished.

On cross-beams 63 is mounted a saw-frame 64 carrying a tilting table 65. The saw-arbor, which is at the exact level of the sanding-roll journal, is coupled thereto by a coupling or pulley 66 made fast to the saw arbor and to the projecting end of the journal above referred to. This supplies the joiner with a slitting saw as a very convenient adjunct in the finishing of an interior. The saw arbor may carry bits 67, and serve as a boring machine by means of the sliding guide 68.

Having thus described my invention, I claim:

1. In a sanding machine, a roll-carrying housing, a sanding roll journaled near one end thereof, a wheel support for the opposite end, carrying wheels adjacent to the ends of the roll and normally concentric therewith axially, and means for adjusting the wheels vertically with respect to said roll.

2. In a sanding machine, a roll-carrying housing, a sanding roll journaled near one end thereof, a wheel support for the opposite end, carrying wheels adjacent to the ends of the roll, and substantially concentric therewith axially, movable supports for said wheels independent of the sanding roll journal bearings, and means for adjusting said supports vertically.

3. In a sanding machine, a roll-carrying housing, a sanding roll journaled near one end thereof, a wheel support for the opposite end, carrying wheels adjacent to the ends of the roll and practically concentric therewith axially, movable supports for said wheels, provided with hollow gudgeons enclosing the roll journal bearings loosely, and means for adjusting said wheel supports vertically.

4. In a sanding machine, a roll-carrying housing, a sanding roll journaled near one end thereof, and having a laterally extended journal adapted to carry a pulley and auxiliary roll, hollow gudgeons surrounding said journal extensions and movable transversely thereof, carrying wheels mounted on said gudgeons, and means for adjusting the gudgeons vertically.

5. In a sanding machine, a roll-carrying housing, a sanding roll journaled near one end thereof, and having laterally extended journals to carry a pulley and auxiliary roll, hollow, journal-surrounding gudgeons movably attached to the sides of the housing, and adjusting screws engaging said gudgeons, whereby the sanding roll may be accurately adjusted with respect thereto, and carrying wheels of a diameter corresponding to that of the roll, mounted on said gudgeons.

6. In a sanding machine, a roll-carrying housing, a sanding roll journaled near one end thereof, and having laterally projecting journals, carrying wheels adjacent to and concentric to the roll hollow, wheel-supporting gudgeons loosely surrounding the roll bearings, means for adjusting them vertically, a motor carried by the housing, a driving pulley thereon, a pulley on one of the extending journals, and a belt carried by said pulleys.

7. In a sanding machine having a roll-carrying housing with a sanding roll mounted near one end thereof, hollow, movable

gudgeons disposed concentrically with respect to the roll, carrying wheels mounted thereon, levers in engagement with said gudgeons, a foot-lever, and links connecting said levers, whereby the carrying wheels may be shifted vertically with respect to the roll by foot-pressure.

8. In a sanding machine of the class designated, having a housing with a sanding roll journaled therein, and axially concentric carrying wheels, a motor mounted on the housing, and belted to the roll, said roll having an extended, pulley carrying journal, a framework forming a fixed seat for the carrying wheels, and an intermediately disposed, vertically adjustable guide-board below the sanding roll to form an accurate backing for material run between it and the sanding roll.

9. In a machine of the class specified, a housing with a motor mounted thereon, a sanding roll journaled near the forward end of the housing, and belted to the motor, an

auxiliary sanding roll outside the housing, supporting wheels concentric to the sanding rolls, a frame adapted to give a fixed support to the sander, and an edging-guide mounted adjustably on said frame and over the auxiliary roll.

10. In a machine of the class specified, a housing with a motor mounted thereon, a sanding roll journaled near its forward end, and belted to the motor, the roll-journal being laterally extended for coupling to other mechanism, carrying wheels concentric to the roll, an oppositely disposed castor, a socket on the housing to receive said castor detachably, a frame having a wheel-seat and a bridge with an up-standing stud to engage said socket, a saw-frame adjacent to the roll, a saw-arbor in alignment with the roll-journal, and a coupling to connect the arbor and journal.

In testimony whereof I affix my signature.

JOHN SCHIMMELPFENNIG.
